BALANCE WEIGHT

Roger Stanley Mallett, Sutton Coldfield, England, assignor
to Dunlop Limited, London, England

Filed Oct. 26, 1973, Ser. No. 409,933

Term of patent 14 years

Int. Cl. D10—04

U.S. Cl. D10—94

FIG. 1

FIG. 2

FIG. 3

FIG. 1 is a left front perspective view of a balance weight showing my new design broken away to indicate indeterminate length;

FIG. 2 is a left elevation view thereof, the right end being a mirror image thereof;

FIG. 3 is a rear elevational view thereof.

I claim:

The ornamental design for a balance weight, as shown and described.
